UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

COIN-CONTROLLED TYPE-WRITING MACHINE.

1,141,559.

Specification of Letters Patent.

Patented June 1, 1915.

Application filed May 14, 1912. Serial No. 697,131.

To all whom it may concern:

Be it known that I, ALFRED G. F. KUROWSKI, a citizen of the United States, residing in Brooklyn borough, in the county of 5 Kings, city and State of New York, have invented certain new and useful Improvements in Coin-Controlled Type-Writing Machines, of which the following is a specification.

10 This invention relates to time and coin-controlled mechanism used in connection with typewriting machines, more particularly to means for starting and stopping such mechanism.

15 Time-controlled mechanism has been used for typewriting machines which are provided with means for normally locking the keys so as to render them inoperative, which locking means is released in any desired 20 manner, as by the insertion of a coin in a slot. Clock-work is provided for throwing the locking means into operation after a certain time so as to again lock the keys. Hitherto in these devices, however, the clock-work kept on running while the typewriter 25 was locked, thus necessitating frequent rewinding.

An object of the present invention is the provision of means whereby the clock-work 30 runs only when the keys are unlocked, and thus it is not necessary to rewind said clock-work except at long intervals. This saves in cost of time and attention given to the machine, and results in economy of maintenance.

35 A further object of this invention is to secure certainty of starting of the clock-work when the latter is inclosed in a locked casing so as not to be gotten at by an unauthorized person.

40 A still further object is to secure certainty of stopping of the clock-work without shock so as not to injure the same.

45 Other features and advantages will hereinafter appear.

In the accompanying drawings, Figure 1 is a perspective view illustrating my invention applied to clock-work used in connection with a locking bar for locking the typewriter keys, parts being broken away and the casing omitted for the sake of clearness. 50 Fig. 2 is an elevation of the mechanism illustrated in Fig. 1 and shown as mounted in a casing, one side of which is removed to display the mechanism, a typewriter key 55 being shown in this figure. Fig. 3 is a detail view illustrating the fly wheel of the clock-work with the combined brake and starter adjacent thereto and in released position therefrom. Fig. 4 is a detail view 60 illustrating in another position, the parts shown in Fig. 3, the combined starter and brake being shown in position to stop the fly wheel. Fig. 5 is a detail view illustrating 65 a typewriter key held in locked position.

The mechanism, part of which is shown in the patent to Rice and Broughton, No. 977,130, November 29, 1910, is illustrated as inclosed in a casing 1, the interior of which cannot be gotten at by an unauthorized person, the latter being able to throw the mechanism into operation only by actuating a movable member such as a bar 2 placed adjacent an opening or slot 3 in the casing. This bar may be operated in any suitable manner, as 70 by the insertion of a coin in slot 3. However, it is clear that it can be operated in various other ways, as for instance by a key or some other device which can be inserted from the exterior of the casing. 75

Bar 2 is normally held upward by a spring 4 and has connected thereto at its lower end a lever 5, fulcrumed on pin 6, the opposite end of this lever having a socket 7 engaging a projection or tooth 8 formed on an 80 arm extending from lever 9 fulcrumed on a pin 10. According to the present invention

85 a pin 11 on the upper end of lever 9, engages an arm 13 of the combined brake and starting lever 12, engaging the fly wheel 14 90 of the clock-work indicated generally as 15. Lever 12 fulcrumed on pin 12^a is normally held by a spring 12^b in position (Fig. 4) so as to engage wheel 14 through a bar 16 extending therefrom and having a toe 16^a 95 adapted to bear against the face of the wheel. Bar 16 is fastened to a projecting portion 17 extending from lever 12. This bar and projection are preferably slightly yielding so as to hug the periphery of wheel 14 when moving into or out of engagement therewith. Moreover, the projection 17 and bar 16 are of such proportion and disposition that the contacting face 16^b of toe 16^a 100 is almost in alinement with the axis of the wheel and the fulcrum of lever 12, so that

when lever 12 is moved from the position shown in full lines in Fig. 4 to the position shown in Fig. 3, the toe 16^a of bar 16 will move for a distance through an arc substantially coinciding with the periphery of wheel 14. It will be seen, therefore, that when lever 12 is moved from the position indicated in full lines in Fig. 4, wherein it frictionally holds wheel 14 from movement, to the position shown in Fig. 3 wherein wheel 14 is disengaged, it will by reason of its resiliency and frictional engagement with the wheel, move for a certain distance together with the wheel, and thus give the clock-work a positive start.

The means for holding lever 12 in its releasing position for a time and then freeing it may be as follows: On lever 5 is formed a projection 18 having a shoulder engaged by a pin 20 projecting through arms 19 pivoted to lever 9, and disposed on each side thereof. When bar 2 is depressed by the operator, the lever 9 is raised, throwing the brake lever into its releasing position, and arms 19 swing so that pin 20 engages projection 18, as shown in Fig. 2. A disk 21 actuated from the clock-work and carrying pins 22 may then strike cam face 23 of an arm 24 pivoted on arms 19 and having a limited pivotal movement with respect thereto, this movement being limited by a pin 25 adapted to engage the upper and lower walls of a slot 26 formed in these arms. When arm 24 is struck by one of the pins 22, the former is swung about its pivot, and through its projecting pin 25 it disengages a latch 27 from pin 20 and allows the latter to move off from projection 18. A spring 28 then retracts lever 9 into position shown in Fig. 1, permitting the brake lever 12 to swing, by force of its spring, into engagement with the wheel 14 to stop the clock-work.

If desired, the disk 21 may be actuated from the clock-work through a pawl and ratchet connection. The pawls may then be thrown out of engagement by levers 5 and 9 when the latter are in position to arrest the clock-work (Fig. 1). It will be understood that lever 5 operates to normally lock the typewriter keys, one of which, indicated 30, is shown in Figs. 2 and 5. This locking is accomplished by the engagement of the beveled shoulder 31, formed on lever 5 with a pin 33 fixed to an arm 32, having rigidly connected thereto, a crank 34, engaging a spring retracted arm 35, having locking bar 36 fast thereto and adapted to be swung under hooks 37 formed on the key levers of the typewriter keys.

Variations may be resorted to within the scope of the invention, and portions of the improvements may be used without others.

Having thus described my invention, I claim:

1. The combination with a manually-operable machine, of a lock for locking the same against actuation, a clockwork, a wheel connected therewith, a brake, a brake-releasing device for throwing the brake out of engagement with said wheel and starting the clockwork, means to release said lock simultaneously with the starting of the clock-work, mechanism for holding said brake-releasing device in position to retain the brake out of engagement with the wheel, and means driven from the clockwork to trip said holding mechanism and cause the brake and lock to be restored.

2. The combination with clockwork, of a wheel connected therewith, a brake lever fulcrumed adjacent said wheel, a slightly yielding projection extending from said lever and engaging the periphery of the wheel at the side thereof diametrically opposite from said lever at a point nearly in a line with the axis of the wheel and the fulcrum of the lever, said projection serving as a friction brake for the wheel when the lever is swung in one direction and also adapted to hug the periphery of the wheel so as to exert a starting impulse thereon when the lever is swung in the opposite direction, mechanism for swinging said lever out of engagement with the wheel, means for locking said mechanism in position to hold the brake lever off the wheel, means driven from said clockwork to trip the locking means and release said mechanism, and means to throw the brake lever into engagement with the wheel when the locking means is tripped.

3. The combination with a manually-operable machine, of a lock to normally prevent operation of the machine, a clock-work, a wheel connected therewith, a brake lever comprising a brake movable into and out of engagement with the wheel to stop and start the clockwork, manually-controlled means to release said lock and actuate the brake lever to release the wheel, said lever mounted to move for some distance in contact with the wheel, and give a starting impulse to the clockwork while being thrown out of engagement with the wheel, whereby the clock-work is started concomitantly with the release of said lock, and means controlled by the clockwork to effect the automatic restoration of the lock and brake.

4. The combination with clockwork, of a wheel connected therewith, a brake mounted adjacent said wheel, a spring to throw the brake into frictional engagement with said wheel so as to exert a braking effect thereon, a brake-releasing device to throw and hold the brake out of engagement with said wheel to release the same, said brake having a path of movement substantially coinciding for some distance with the path of movement of the wheel, the continued contact between the brake and wheel during the release of

the latter serving to give a starting impulse to the same, means to restrain the brake-releasing device in operative position, and a trip driven by the clockwork to release 5 said restraining means and permit the brake to be thrown by its spring to braking position.

5. The combination with clockwork, of a wheel connected therewith, a lever fulcrumed 10 adjacent said wheel, a slightly yielding projection extending from said lever and frictionally engaging the wheel at a point nearly in a line with the axis of the wheel and the fulcrum of the lever, said projection serving as 15 a friction brake for the wheel when the lever is swung in one direction, and also adapted to hug the periphery of the wheel so as to give a starting impulse thereto when the lever is swung in the opposite direction, 20 a spring to apply the brake, an arm to hold the brake off the wheel, a latch to hold said arm in operative position, and a trip driven by the clockwork to trip the latch and permit the spring to apply the brake.

25. 6. The combination with clockwork, of a wheel connected therewith, a lever fulcrumed adjacent said wheel, a slightly yielding projection extending from said lever and frictionally engaging the periphery of 30 the wheel at a point nearly in line with the axis of the wheel and the fulcrum of the lever, and on the opposite side of the wheel axis from the said fulcrum, said projection serving as a brake for the wheel when the 35 lever is swung in one direction, and also adapted to hug the periphery of the wheel so as to give a starting impulse thereto when the lever is swung in the opposite direction, yielding means for throwing the lever into engagement with the wheel, positive means for 40 throwing and holding the lever out of engagement with the wheel, a device set by the operation of said last-named means to hold the latter in operative position, and time-controlled means operated by the clockwork 45 to release said device and permit the lever to be thrown into engagement with the wheel.

7. The combination with a manually-operable machine and a lock to normally prevent the operation of the machine, of a clockwork comprising a brake wheel and a friction brake normally holding the brake wheel and preventing the clockwork from running, 50 means to release said lock and throw the brake off said wheel, said brake operable as it is thrown off the wheel to impart a positive starting impulse to the clockwork, and means controlled by the clockwork to effect 55 the restoration of said brake and lock to stop the clockwork and to prevent operation of the machine.

8. The combination with a manually-operable machine and means to lock it against 60 clockwork, mechanism to simultaneously re-

lease the lock and the brake and impart a positive starting impulse to the clockwork, and mechanism driven by the clockwork and operable after a time interval to effect the restoration of the brake and lock.

70

9. The combination of clockwork, a brake for the clockwork, a brake lever operable when unrestrained to apply the brake, a restraining device operable when in one position to restrain the brake lever and prevent 75 the brake from being applied, a manually-operable machine, a lock for locking the machine against actuation, means to release said lock and put it under the control of the clockwork to be restored thereby, means to operate said restraining device when the lock is released and thereby release the brake, a latch to hold said restraining device in operative position, and means to release the latch when the lock is restored and thereby cause the brake to be applied and stop the clockwork.

80

85

10. The combination with a manually-operable machine and a lock for normally locking the machine against actuation, of a 90 clockwork having an oscillating wheel, a device mounted to enter into frictional contact with the periphery of said wheel to form a brake therefor, means operable independently of the clockwork to release said lock and to release the brake device from said wheel while causing it to frictionally move the wheel and thereby impart a starting impulse to the wheel, and means controlled by the clockwork to automatically 100 restore the lock and effect a restoration of the brake device to stop the clockwork.

95

11. The combination of a manually-operable machine, a lock normally locking the machine against operation, a clockwork, 105 means to normally restrain the clockwork from operation, means to release said lock and place it under the control of the clockwork to be restored thereby, means to release said restraining means and impart a 110 starting impulse to the clockwork when the lock is released, and means to restore said restraining means and stop the clockwork when the lock is restored.

105

12. The combination of a manually-operable machine, a lock for normally locking the same against actuation, a clockwork, means normally restraining the clockwork from operation, means to release said lock and put it under the control of said clockwork to be restored thereby, means for releasing said restraining means simultaneously with the release of said lock, and means to restore said restraining means simultaneously with the restoration of said 120 lock.

115

13. The combination of a manually-operable machine, a lock therefor, a clockwork for predetermining the moment of restoring the lock after the same has been unlocked,

130

and means to automatically stop the clock-actuation, of a clockwork, a brake for the work when the machine is locked.

14. The combination of a typewriter mechanism, a lock adapted to lock the same, time-controlling mechanism for predetermining the moment of operation of the lock to lock the typewriter mechanism after the same has been unlocked, and means to automatically start and stop the time-controlling mechanism concomitantly with the unlocking and locking of the typewriter mechanism.

15. The combination of a typewriter mechanism, a lock therefor, clockwork, means to prevent the clockwork from running while the typewriter mechanism is locked, manually-controlled means to release the lock and start the clockwork, and means controlled by the clockwork for restoring the lock and stopping the clockwork at the end of a pre-determined time interval.

16. The combination of a typewriter mechanism, a movable device to prevent the same from being manipulated, said movable device being normally in effective position, means to move said device to ineffective position and permit the manipulation of the typewriter mechanism, a time-controlling mechanism, means to set the time-controlling mechanism in operation when said device is moved to ineffective position, said time-controlling mechanism operative to restore said movable device after a predetermined time

limit, and brake mechanism controlled by said time-controlling mechanism, and automatically operated to stop the latter when said movable device is restored.

17. The combination with a typewriting machine and a movable device normally effective to prevent the manipulation of said machine, of a clockwork, means to move said movable device to ineffective position and place it under the control of the clockwork, the latter operable to restore said device to effective position after a predetermined time interval, and means to automatically start the clockwork when said device is moved to ineffective position and to stop the clockwork when the device is moved to effective position.

18. The combination of a typewriter mechanism, a device for disabling the typewriter mechanism, clockwork, manually-controlled means to render said disabling device ineffective and to concomitantly start the clockwork, said device when rendered ineffective being taken out of manual control and placed under the control of the clockwork to be restored thereby to normal effective position, and means to automatically stop the clockwork when said device is restored.

ALFRED G. F. KUROWSKI.
